UNITED STATES PATENT OFFICE.

CHARLES H. JENKINS, OF LEBANON, NEW HAMPSHIRE, ASSIGNOR OF ONE-HALF TO FRANK B. KENDRICK AND WILLIAM F. DAVIS, OF LEBANON, NEW HAMPSHIRE.

WATCHMAKER'S GAGE.

SPECIFICATION forming part of Letters Patent No. 738,723, dated September 8, 1903.

Application filed January 31, 1902. Serial No. 91,973. (No model.)

To all whom it may concern:

Be it known that I, CHARLES H. JENKINS, a citizen of the United States, residing at Lebanon, in the county of Grafton and State of New Hampshire, have invented certain new and useful Improvements in Watchmakers' Calipers, of which the following is a specification, reference being had therein to the accompanying drawings.

10 My invention relates to improvements in calipers which are especially adapted for the use of watchmakers, and has for its object to provide a simple, efficient, and easily-adjustable mechanism not only for measuring the 15 diameter or thickness of various objects, but also for testing the balance-wheel or other like wheel of a watch or other similar device for truth and poise—that is to say, to provide a simple and efficient watchmaker's tool that 20 may be readily adjusted and used not only as calipers, but also as a truing and poising tool.

The invention consists of the novel features of construction hereinafter set forth and described, and more particularly pointed out in the claims hereto appended.

Referring to the drawings, Figure 1 is a plan view of the tool. Fig. 2 is a plan view of the under side. Fig. 3 is a plan view shown 30 partly in section. Fig. 4 is an end elevation. Fig. 5 is a detail view of the means for supporting and adjusting the caliper-points, shown partly in section, said section being taken on the line 5-5 of Fig. 3 looking in the 35 direction of the arrow. Fig. 6 is a perspective view of the bolt connecting the caliper-arms. Fig. 7 is a perspective view of the said arms disconnected and partly broken away. Fig. 8 shows a modification of means for attaching the indicator-bar and finger-bar to 40 the caliper-arm. Figs. 9 and 10 are detail views of the same.

Like letters of reference refer to like parts throughout the several views.

45 *a* and *b* denote symmetrically-formed bars or arms, made, preferably, of metal, each of which is provided with a circular recessed portion *c* and with the shoulders *d'*, *d²*, *d³*, and *d⁴*. These recessed portions extend half-way into the bar and are each provided with

a central opening *e*. The said recessed portion, the shoulders, and the central opening of one bar correspond in size and shape with the recessed portion, the shoulders, and the central opening of the other bar—that is say, 55 the bars *a* and *b* are symmetrically and similarly formed in every respect. These bars are assembled to form a double pair of caliper-jaws *m m* and *n n*, as shown in Figs. 1 to 3, inclusive, by placing the bar *a* over the 60 bar *b*, so that the recessed portions will dovetail or fit together and the central opening therein register, and by passing a headed bolt *f* through the said openings and by securing the same to a cap or plate *g*, 65 through which the bolt *f* likewise passes, by means of screws *h h*, similar to the pillar-screw of a watch, said screws engaging with screw-threaded recesses *i i* in the end of said bolt *f*. By this construction a smooth, neat, 70 and strong pivot or joint is made and at the same time one which will permit of the caliper-arms being readily taken apart when desired to adjust the same. The shoulders *d'*, *d²*, *d³*, and *d⁴* are so constructed and arranged 75 that in a full-sized tool there is a space of about one-sixteenth of an inch between each pair of opposed shoulders when the arms are in the position shown in Figs. 1 and 2 of the drawings to permit the jaws to move toward 80 and from each other.

k is a plunger actuated by the spring *k'*, both the said plunger and spring being inserted in a hole or recess drilled in the arm *a*, the function of this mechanism being to 85 force the caliper-jaws toward each other, the force of the spring *k'* causing the plunger *k* to press or push against the shoulder *d⁴* of the bar *b*, and thereby causing the caliper-jaws to move toward each other until stopped 90 either by the shoulders *d²* and *d³* pressing against each other or by the inner end of the adjusting stop-screw *l* pressing against the shoulder *d²* of the bar *b* whenever the inner end of said stop-screw projects beyond the 95 face of the shoulder *d²* of the arm *a*. The stop-screw *l* is provided with a head *l'* and passes through the arm *a* and is adapted to bear against the shoulder *d²* of the bar *b*, and its function is to overcome the force of the 100

spring-plunger k and to stop the caliper-jaws from moving toward each other whenever desired. It does not prevent, however, the caliper-jaws from being moved farther apart, 5 a feature which is of great advantage when it is desired to remove the wheel under examination from the caliper bearings or centers with the intention of reinserting it again between the caliper-centers for reexamination and proof, as will be hereinafter more fully stated.

k^2 is a knurled screw passing through the arm a and adapted to bind upon the plunger k , and its function is to hold the plunger back 15 whenever it is not desirable to have the arms spring-acting. If for any purpose it be desired to lock the jaws, so as to fix them in a certain adjusted relation, the set-screw k^2 is bound against the plunger k and renders it 20 inoperative and at the same time prevents the separation of said jaws. This, in conjunction with the set-screw l' or other means of limiting the reverse movement of the jaws, will serve to effectually lock the device in adjusted position. 25

In the jaws $m m$ of the arms a and b are formed or secured suitable bearings or centers $m' m'$ to receive the shaft of the wheel—for example, the center-wheel of a watch—to 30 be examined. These ends of the calipers are especially adapted for the examination of wheels heavier and larger than the balance-wheel of a watch.

$o o$ denote split draw-in studs, each provided with an opening p , adapted to receive the points having recessed ends, and said studs are also provided with a screw-threaded portion which passes through the jaws $n n$ and with which screw-threaded portion 35 the thumb-nut q is adapted to engage. The jaws $n n$ are especially adapted for the examination of the more delicate wheels of a watch, such as the balance-wheel and the like.

40 t is an indicator-bar attached to and supported upon the arm a by means of a taper-headed screw or stud u , carried by the arm a , the said bar having one or more holes $v v$ near one end and the said end being separated or split, as at w , so as to form a spring to bind on the taper head of said screw or stud and at the same time permit of the bar being readily detached from the arm. The opposite end of said bar t is preferably free, 45 the said bar being maintained in the desired relation to the said jaws by the spring connection heretofore described.

x denotes an indicator-finger or auxiliary indicator-bar attached to the indicator-bar t 50 by means of a taper-headed stud or screw y and having one or more holes $z z$ and separated or split, as at z' , to form a spring to bind on the taper head of said screw or stud y and at the same time permit of the finger-bar being readily detached from the indicator-bar. 55

The indicator-bar t , carrying the indicator-

finger or auxiliary bar x , may be attached to the stud n' when it is desired to use it in connection with jaws $m m$. The indicator-bar t 70 may, however, be attached to the caliper-arm by the construction shown in Figs. 8 and 9—that is, by a split stud or screw y^2 , secured to the indicator-bar, which stud or screw is adapted to enter a hole in the caliper-arm, 75 and thereby form a spring connection between said bar and said arm and at the same time permit of the said bar being readily detached from the said arm. The indicator-finger may be attached to the indicator-bar 80 in like manner—that is, the split stud or screw y^3 , Fig. 10, is adapted to enter a hole in the indicator-bar and connected therewith in the same manner that the split stud or screw y^2 is connected with the caliper-arm. 85

The mode of operation of the above-described device in so far as it has not already been disclosed is as follows: When it is desired, for example, to test the balance-wheel of a watch, the stop-screw l is set and adjusted so that the points or centers $r r$ will bear with sufficient force against the journals of the wheel, so as to allow the wheel to revolve freely without looseness. The function of the stop-screw l , as has been already 90 stated, is to overcome the force of the spring-plunger k , thereby relieving the journals of the wheel from too great pressure of the jaws and reducing the tendency to bend and distort the wheel to a minimum. By this construction the jaws may be adjusted with great convenience and extreme delicacy so as not to injure the wheel under examination. The wheel having been adjusted between the points, as above stated, it becomes necessary 95 to adjust the points so that their axes shall lie in the same straight line. This is accomplished by turning the points supported by the split draw-in studs by means of the hand or a key-lever (not shown) until the axes of 100 said points appear to the eye to be in the same straight line. The points are then securely held in position by the said studs by turning the thumb-nut q . This construction 105 avoids the difficulty which occurs when the caliper-arms are hinged or pivoted together, for when they are adjusted for different sizes of wheels the points or bearings move in arcs, and consequently the axes of the two bearings or centers will not lie in the same straight 110 line, and therefore the use of the device is limited, so far as a reliable test is concerned, to a few sizes of wheels, because the axes of the bearings are at an angle to the axes of the wheel. By the use of the adjustable 115 points above described accurate results may be obtained for a much greater variety of sizes of wheels than with instruments not provided with such adjustable points, and, furthermore, a quick and ready means is 120 provided not only for adjusting the bearings or points, but also for changing the same. The wheel having been perfectly adjusted as 125 above stated, the indicator-finger carried by

130

the indicator-bar is adjusted to the rim of the wheel and the wheel revolved in the ordinary way to test the wheel for truth and poise. When this has been determined, the

5 jaws are spread apart and the wheel removed and altered if found defective and replaced to verify the work. This can readily be done, because the opening and closing of the jaws does not disarrange the adjustment of any 10 of the parts, the spring returning the bearings or centers and indicator-finger to the same positions as previously set.

What I claim, and desire to secure by Letters Patent, is—

15 1. In a device of the class described, a pair of jaws one of which is pivotally movable relative to the other, means whereby a bearing may be secured to each jaw, adjusting mechanism connected with each means

20 whereby it may be adjusted independently of its jaw in a plane transverse to the axis of said pivotal movement and a finger-bar adapted to be supported by said jaws adjacent to said bearings.

25 2. In a device of the class described, a pair of jaws one of which is pivotally movable relative to the other, means whereby a bearing may be detachably secured to each jaw, adjusting mechanism connected with each

30 means whereby it may be adjusted independently of its jaw in a plane transverse to the axis of said pivotal movement and a finger-bar adapted to be supported by said jaws adjacent to said bearings.

35 3. In a device of the class described, a pair of jaws, one of which is pivotally movable relative to the other, means whereby a bearing may be secured to each jaw, adjusting mechanism connected with each means where-

40 by it may be adjusted independently of its jaw in a plane transverse to the axis of said pivotal movement and a finger-bar adapted to be supported by said jaws adjacent to said bearings.

45 4. In a device of the class described, a pair of jaws, one of which is pivotally movable relative to the other, a split draw-in stud carried by each jaw whereby a bearing may be detachably secured thereto and whereby ad-

50 justment of said bearings in a plane transverse to the axis of said pivotal movement independently of its jaw may be had, and a thumb-nut whereby said stud may be released to admit of such adjustment and reset in any desired position.

55 5. In a device of the class described, the combination of a pair of jaws, a pivotal connection therefor, said jaws being provided adjacent to said connection with opposed

60 shoulders, whereby the pivotal movement in each direction is limited, a spring-actuated plunger seated in a recess in one of said shoulders and adapted to bear against the opposing shoulder, whereby said jaws are normally forced toward each other and means

65 whereby said plunger may be set against movement.

6. In a device of the class described, the combination of a pair of jaws, a pivotal connection therefor, said jaws being provided adjacent to said connection with opposed shoulders, whereby the pivotal movement in each direction is limited, a spring-actuated plunger seated in a recess in one of said shoulders and adapted to bear against the opposing shoulder, whereby said jaws are normally forced toward each other until other opposing shoulders meet, and adjustable means in connection with said last-mentioned shoulders, whereby the movement of said jaws in one direction only may be regulated.

70 7. In a device of the class described, the combination of a pair of jaws, a pivotal connection therefor, said jaws being provided adjacent to said connection with opposed shoulders, whereby the pivotal movement in each direction is limited, a spring-actuated plunger seated in a recess in one of said shoulders and adapted to bear against the opposing shoulder, whereby said jaws are normally

75 forced toward each other until other opposing shoulders meet, and a set-screw capable of being drawn entirely within one of said last-mentioned shoulders and adapted to bear against the opposing shoulder, whereby the movement of said jaws may be regulated.

80 8. In a device of the class described, the combination of two symmetrical bars provided respectively with a circular recess intermediate their ends and diametrically opposite jaws, and a pivotal connection between said bars centrally of said recesses, comprising a cap, a headed bolt passed through said bars and cap, and a plurality of screws adapted to engage respectively the shank of said bolt and said cap.

85 9. In a device of the class described, the combination of a pair of jaws, a pivotal connection therefor, said jaws being provided with opposed shoulders adjacent to said connection, whereby the movement of said jaws

90 in each direction is limited, a spring-actuated plunger seated in a recess in one of said shoulders and adapted to bear against the opposing shoulder, whereby said jaws are forced toward each other until other opposed shoulders meet, adjustable means in conjunction with said last-mentioned shoulders whereby the movement of said jaws under the influence of said plunger may be regulated, and means whereby said plunger may be set in any desired position to lock the device.

10. In a device of the class described, a pair of jaws, a stud carried by one of said jaws and an indicator-bar having a plurality of openings therein, said stud being adapted to pass through said openings respectively and be frictionally engaged by said bar.

11. In a device of the class described, a pair of jaws, an indicator-bar provided with a bifurcated spring portion, and means in conjunction with said spring portion whereby said bar may be secured to one of said jaws.

12. In a device of the class described, a pair of jaws, an indicator-bar; a stud on said bar, means whereby said bar may be secured relative to said jaws, a finger-bar having a plurality of openings therein adapted to engage said stud, whereby it may be frictionally and detachably secured to said indicator-bar by means of said stud.
13. In a device of the class described, a pair of jaws, an indicator-bar, means whereby said bar may be secured relative to said jaws, a finger-bar having a bifurcated spring portion, and means in connection with said spring portion whereby said finger-bar may be secured to said indicator-bar.
14. In a device of the class described, a pair of jaws one of which is pivotally movable relative to the other, means whereby a bearing may be secured to each jaw, adjusting mechanism connected with each means whereby it may be adjusted independently of its jaw in a plane transverse to the axis of said pivotal movement, means for imparting pivotal movement to said jaw and a finger-bar adapted to be supported by said jaws adjacent to said bearings.
15. In a device of the class described, a pair of jaws one of which is pivotally movable relative to the other, means whereby a bearing may be detachably secured to each jaw, adjusting mechanism connected with each means whereby it may be adjusted independently of its jaw in a plane transverse to the axis of said pivotal movement, means for imparting pivotal movement to said jaw and a finger-bar adapted to be supported by said jaws adjacent to said bearings.
16. In a device of the class described, a pair of jaws one of which is pivotally movable relative to the other, means whereby a bearing may be secured to each jaw, adjusting mechanism connected with each means whereby it may be adjusted independently of its jaw in a plane transverse to the axis of said pivotal movement, and set in a desired position, means for imparting pivotal movement to said jaw and a finger-bar adapted to be supported by said jaws adjacent to said bearings.

In witness whereof I have hereunto set my signature, this 16th day of January, 1902, in the presence of two witnesses.

CHARLES H. JENKINS.
